[57] CLAIM

The ornamental design for a motorcycle body, as shown and described.

DESCRIPTION

FIG. 1 is a perspective view taken from the left and in front of a motorcycle body according to our novel design;

FIG. 2 is a perspective view from the right side and in front of the motorcycle body according to our novel design;

FIG. 3 is a left side view of the motorcycle body according to our novel design;

FIG. 4 is a right side view of the motorcycle body according to our novel design;

FIG. 5 is a perspective view taken from the left rear side of the motorcycle body according to our novel design;

FIG. 6 is a perspective view taken from the right rear side of the motorcycle body according to our novel design;

FIG. 7 is a front view of the motorcycle body according to our novel design;

FIG. 8 is a rear view of the motorcycle body according to our novel design; and,

FIG. 9 is a top view of the motorcycle body according to our novel design.

Features such as the kick stand, mirrors, and wheels shown in dash lines depict the environment and do not form part of the claimed design.
